[51] Int. Cl. F02f 1/00

An internal-combustion engine cylinder head assembly comprises an induction passage having two portions in the form of surfaces of revolution generated about different axes. The axis of the downstream portion is coincident with the axis of the inlet valve, and the plane of symmetry of the passage contains the axis of the valve and the axis of the engine cylinder.

INTERNAL-COMBUSTION CYLINDER HEAD ASSEMBLIES

BACKGROUND OF THE INVENTION

1. Field of the Invention

The present invention relates to cylinder head assemblies for internal-combustion engines.

2. Description of the Prior Art

To obtain from an internal-combustion engine a high specific power, equal to at least 80 H.P. S.A.E., for example, it is necessary that the cylinders be satisfactorily charged with fuel-air mixture. The conditions to be fulfilled for this purpose are easier to provide in the portion of the induction system which lies outside the cylinder head than for the portion within the cylinder head since the shape and surface finish of induction passages externally of the cylinder head can be provided as desired.

Induction passages within the cylinder head should create only very small pressure drops, as can be ensured by uniformly shaping the passage cross-section, and by providing steady and smooth progressions from section to section and a good surface finish on the passage walls.

In any given engine, the dimensions and surface finish of the induction passages feeding each of the cylinders should vary within the narrowest possible limits, being to all intents and purposes identical for all cylinders, failing which there may be a serious lack of balance, such as to prevent proper running and to shorten the life of the engine. This identity of dimensions and surface finish must also be preserved from engine to engine, to avoid variation in the maximum output power of identical engines.

The cylinder heads of high-power engines can be made of aluminum alloy. In mass production, pressure casting enables correct shaping and surface finish to be obtained. The mould stripping conditions, however, prevent the desired shapes from being achieved without resort to expedients such as, a joint-plane extending into the induction passage or a separately fitted passage.

It has been found experimentally that optimum specific power is obtained from an induction passage that is of circular section throughout, the cross-sectional area increasing steadily in the direction of flow. Such passages can be produced by final dressing, as practised in the case of racing engines. Protracted, highly delicate work will yield a proper surface finish, but it will not ensure uniformity between the shaping of one passage and the next.

The use of pressure casting, with a joint-plane within the passage, not only necessitates additional parts, but adversely affects the maximum power output because of the irregularities introduced by the joint.

An object of the present invention is to provide a cylinder head assembly having at least one induction passage in which the flow cross-section steadily increases in area from the point of admission to the cylinder head to the valve seat, but which can nevertheless readily be machined in mass production.

SUMMARY OF THE INVENTION

According to the present invention, there is provided in an internal-combustion engine cylinder head assembly means defining at least one induction passage for

feeding fuel-air mixture to an engine cylinder, and an inlet valve controlling flow through the induction passage, said induction passage being symmetrical about a plane containing the axis of the cylinder and the axis of the inlet valve, and having a first or upstream portion in the form of a surface of revolution generated about a first axis, and a second portion downstream from the first portion and in the form of a surface of revolution generated about a second axis coincident with the axis of the inlet valve.

The two portions of the passage can be interconnected by a portion of a sphere to which they are tangential. They may be frusto-conical at least for part of their length.

15 In one preferred embodiment of the invention, the cylinder head contains three successive portions in the form of surfaces of revolution generated about different axes. The first or upstream portion in the direction of flow and the intermediate portion preferably being interconnected by a portion of a sphere to which they are tangential.

BRIEF DESCRIPTION OF THE DRAWINGS

25 Embodiments of the invention will now be described, by way of example only, with reference to the accompanying diagrammatic drawings, in which:

FIG. 1 is a fragmentary cross-section of one embodiment of a cylinder head assembly in accordance with the invention, the section being taken on a plane containing the axis of an inlet valve and cylinder of the associated engine;

20 FIG. 2 is an elevation showing the shape of an induction passage, of the cylinder head;

FIG. 3 is a fragmentary cross-section similar to FIG. 1, of another embodiment of a cylinder head assembly; and

25 FIG. 4 is a section taken on line A—A of FIG. 3.

DESCRIPTION OF THE PREFERRED EMBODIMENTS

40 As shown in FIG. 1 a cylinder head assembly 1 to be positioned at one end of a cylinder having an axis OX, has a machined induction passage 2, and an exhaust passage 3. The induction passage 2 ends in a venturi-shaped seat 4, for an inlet valve 5, the stem 6 of which moves in the direction of its longitudinal axis OY.

45 The induction passage 2 is symmetrical about a plane containing the axes OX and OY. The induction passage 2 comprises, taken in the direction of flow of the fuel-air mixture, a cylindrical portion 2a having an axis ZZ, joined by a toroidal surface 2b, to a frusto-conical portion 2c, co-axial with the cylindrical portion 2a; the frusto-conical portion 2c lies within the acute angle formed between the axis OY and a line extending at right angles to the axis OX. The portion 2c is tangential to a portion 2d which forms part of a sphere 7 having its centre at 8, the point of intersection of the axes OY and ZZ. The diameter of this sphere is slightly smaller than D, the diameter of the upstream edge of the seat 4. The spherical portion 2d is joined to the seat 4 by a frusto-conical portion 2e having a base diameter D. The portion 2e is followed by a short cylindrical portion 2f, the axes of the portions 2e and 2f being coincident with the axis OY and being interconnected by a toroidal portion 2g. As can be seen from FIG. 2, the frusto-conical portion 2c meets the frusto-conical portion 2e along a curve 9.

It can also be seen, from FIGS. 1 and 2, that a point 10 on the curve 9 situated in the plane of symmetry of the passage 2 (the plane of FIG. 1) also lies on the cylindrical portion 2f.

Calculation of the various cross-sectional areas of the passage 2 shows that the cross-sectional area increases substantially uniformly in the direction flow, reaching a maximum at the connection to the seat 4; it is thus possible to obtain high values of specific power. Moreover, the passage 2 can readily be machined for mass production purposes in two stages, namely by boring along the axis ZZ using an expanding tool, the advance of which is programmed according to the profile desired, and by milling along the axis OY with a ball-ended profile cutter.

The induction passage 2' in the cylinder head assembly shown in FIGS. 3 and 4 is likewise symmetrical about a plane containing the axes OX and OY. It comprises, taken in the direction flow, a cylindrical portion 2'a having an axis Z₁—Z₁, connected by a toroidal surface 2'b to a frusto-conical portion, tangential c co-axial with the cylindrical portion 2'a. The portion 2'c is tangential to a portion 2'd, which forms part of a sphere 7 having its centre at 8.

The spherical portion 2'd is joined to a portion 2'e, having an axis Z₂—Z₂, the latter lying between the axes Z₁—Z₁ and OY and passing through the centre 8. As shown, the portion 2'e is cylindrical (but can alternatively be frusto-conical) and meets the portion 2'c which it intersects along the curve 9'.

The portion 2'e is joined to the seat 4 by a frusto-conical portion 2'f which is followed by another cylindrical portion 2'g, the axis of these last two portions being co-incident with the axis OY. The portions 2'e and 2'f intersect along a curve 10.

The present invention is not limited to the embodiments described and illustrated. For example, the surfaces of revolution which form the induction passage 2 could have different longitudinal mid-planes, provided that the axis of revolution of the downstream portion or portions coincide with the axis OY.

What is claimed is:

1. An internal combustion engine intake passage for a cylinder comprising:
  - a. an upstream portion;
  - b. an intermediate portion connected to said upstream portion and in open communication therewith;
  - c. a downstream portion connected at the downstream end of said intermediate portion and in open communication therewith;
  - d. a valve seat positioned at the downstream end of said downstream portion;
  - e. a valve adapted to contact said seat to close and open said passage, said valve being positioned with its longitudinal axis intersecting the axis of the cylinder at an angle;
  - f. the cross-sectional area of said passage substantially increasing in the direction of flow from said upstream portion to said valve seat;
  - g. said upstream portion being defined by a first surface of revolution generated about a first linear axis

- longitudinally disposed within and extending the entire length of said upstream portion and intersecting said longitudinal valve axis at an angle;
- h. said intermediate portion being defined by a second surface of revolution generated about a second linear axis longitudinally disposed within and extending the entire length of said intermediate portion and intersecting said first axis and said longitudinal valve axis at different angles;
  - i. said downstream portion being defined by a third surface of revolution generated about a third linear axis longitudinally disposed within and extending the entire length of said downstream portion and coincident with said longitudinal axis of said valve; and
  - j. said upstream, intermediate and downstream portions being symmetrical about a plane containing said cylinder axis and said longitudinal valve axis.
2. An assembly as claimed in claim 1, in which said valve seat is of venturi shape.
  3. An assembly as claimed in claim 1 in which said upstream portion of the passage is frusto-conical at least for part of its length.
  4. An assembly as claimed in claim 3, in which said upstream portion comprises a cylindrical portion connected to said frusto-conical portion.
  5. An assembly as claimed in claim 4, in which said upstream portion comprises a toroidal portion connecting said cylindrical portion to said frusto-conical portion.
  6. An assembly as claimed in claim 1 in which said downstream portion of the passage is frusto-conical, at least for part of its length.
  7. An assembly as claimed in claim 6 wherein said downstream portion further comprises a cylindrical portion connecting said frusto-conical portion to said valve seat.
  8. An assembly as claimed in claim 1 in which said longitudinal axis of said valve is inclined in relation to said axis of said cylinder and said first axis is situated in the acute angle formed between said longitudinal axis of said valve and an imaginary line extending at right angles to said axis of said cylinder.
  9. An assembly as claimed in claim 1 wherein said downstream portion of said passage comprises a frusto-conical portion and a cylindrical portion, said frusto-conical portion of said downstream portion being connected to said intermediate portion of said passage and said cylindrical portion connecting said frusto-conical portion to said valve seat, said intermediate portion and said cylindrical portion and said frusto-conical portion of said downstream portion intersecting said plane containing said axis of said cylinder and said longitudinal axis of said valve at a point lying on said plane.
  10. An assembly as claimed in claim 1 in which said passage further comprises a partially spherical portion disposed between and connecting said upstream and intermediate portions, said upstream and intermediate portions being tangential to said partially spherical portion.
